AIR CONDITIONING DEVICE

Don E. Dasher, Harrison Township, Montgomery County, Ohio, assignor to Trupar Manufacturing Company, Dayton, Ohio, a corporation of Ohio

Application March 27, 1933, Serial No. 662,937

17 Claims. (Cl. 62—134)

This invention relates to new and useful improvements in air conditioning devices.

It is one of the principal objects of my invention to provide an air conditioning device of the 5 ceiling fan, bracket or pedestal type that will distribute the conditioned air laterally in all directions. It effects an equal gravitational distribution, and even diffusion, of the conditioned air without draft or blast.

10 It is another object of the invention to provide a pump, preferably driven from the fan shaft, for removing the condensation from the air conditioning device.

15 It is another object of my invention to provide electric lights on the fan housing for direct or indirect lighting.

20 It is another object of my invention to provide means for discharging the air laterally from the fan, or for drawing it in through the sides and discharging it through the top or bottom of the fan housing.

Other important and incidental objects will be brought out in the following specification and particularly set forth in the subjoined claims.

25 In the accompanying drawings illustrating the different forms of embodiment of my invention, Figure 1 is a longitudinal-sectional view taken through my ceiling type of fan for discharging the air laterally in all directions. Figure 2 is a side elevational view of a wall bracket type of fan. Figure 3 is a side elevational view of a pedestal type of fan. Figure 4 is a longitudinal sectional view through the fan portion of the pedestal unit. And Figure 5 is a longitudinal sectional view taken through a ceiling type of fan unit in which the air enters at the sides and top and is discharged laterally from the bottom in all directions.

40 Referring to the accompanying drawings for a detailed description of the different forms of embodiment of my invention illustrated therein, the numeral 1 in Figure 1 designates a ring adapted to be secured to a room-ceiling 2 and to receive bracket screws 3. The ring 1 is provided with a cross member 4 which is attached to the ceiling by a stud 5.

45 Secured to the ring 1 by the screws 3 are bracket arms 6 which terminate at their lower ends in vertical portions 7. The latter are connected by fastening elements such as bolts 8 to the upper end of a vertical tubular member 9 to which there is secured by screws 10 an ornamental casing 11 that surrounds the bracket arms and is itself attached to the ring 1. (See 50 Figure 1.)

Secured by screw bolts 12 to the lower end of the tubular member 9, are the upturned ends of bracket arms 13. The latter, in turn, are secured to vertical arms 14 which terminate in long horizontal ends 15. Attached to the horizontal ends 15 of the arms 14, are cylindrical rubber pads 16 that are recessed to fit holes in a plate 17 that has a central, flanged neck portion 18. By means of the pads 16, and studs 19 which pass through them the plate 17 is supported by 10 the arms 14 in a substantially noiseless manner.

Secured to similar rubber pads 20 connected by screws 21 to the plate 17 near its tubular neck portion 18, are bracket arms 22, 22 attached at their upper ends by screws 23 to a vertically disposed electric motor 24 to support the same. Surrounding the motor 24 is a cylindrical housing 25 and a dome-shaped cover 26 above it. The housing 25 is secured by flanged foot members 27 to the horizontal portions of the arms 14, 20 while the dome-shaped cover 26 has a neck part 28 which is attached by screws 29 to the tubular member 9. (See Figure 1.) The members 26 and 25 form together an ornamental casing for the motor 24 and its surrounding parts.

Projecting downwardly from the motor 24 is an armature shaft 30 to which is attached the hub 31 of a conventional centrifugal, multi-vane fan 32. Surrounding this fan is an evaporator 33 preferably comprising a spiral expansion coil 30 34 supported by U-rods 35. These U-rods are secured at their upper ends to bars 36 which are attached to the horizontal portions of the arms 14, below the pads 16 and washers 37, by the studs 19.

Depending from the outer, flat annular edge portion 38 of the plate 17, is a circumferential series of studs 39 with ornamented heads, and carrying on their lower ends ornamental nuts 40. Secured to these studs at suitable distances apart, 40 are flat rings 41 between which conditioned air is discharged laterally outward by the fan 32 in all directions, as indicated by the arrows in Figure 1. This air is cooled by the expansion coil 34 between whose spirals it passes in its outward course.

The refrigerant is introduced into the expansion coil 34, and discharged therefrom, by the following means. Referring to Figure 1, the liquid refrigerant is drawn from a compressor (not shown) through a tube 42 into a cooling coil 43 which surrounds the bracket arms 14, and is held against them by vertical retaining members 44 with beveled ends, attached to the bracket arms by long studs 45. (See Figure 1.)

25

30

35

40

45

50

55

The lower end of the coiled liquid refrigerant, inlet tube 42 communicates with an expansion valve 46 from whence the gaseous refrigerant flows through a tube 47 into the expansion coil 34 which surrounds the centrifugal fan 32, to cool the air set in lateral motion in all directions by it.

Through a tube 48 connected with the outlet end of the expansion coil 34, the cool gaseous refrigerant is discharged into a tubular sleeve or jacket 49 which surrounds the inlet tube 42, to cool the warm liquid refrigerant which enters the latter. The sleeve 49 terminates in a T-fitting 50 from which the gaseous refrigerant is returned to the compressor through a tube 51 which, with the liquid inlet tube 42, passes through the depending tube 9, ring 1 and ceiling 2, to said compressor.

The moisture or water of condensation which the expansion coil 34 abstracts from the air forced past it by the fan 32, drops upon a pan 52 secured to the studs 39 immediately above the nuts 40. This pan 52 has a central flanged neck portion 53 around which studs 54 project downwardly from the pan. Secured to the lower ends of these studs 54 by ornamental nuts 55 is a pan 56 into which the water of condensation is discharged by the pan 52.

Secured to the studs 54, are two flat rings 57 having downwardly inclined portions for deflecting the air that enters between them, downwardly and inwardly for entrance through the central open portions of said rings to the centrifugal fan 32 which is directly above the open neck portion 53 of the pan 52, as indicated by the arrows in Figure 1.

For the purpose of removing the water of condensation from the bottom pan 56, I provide a pump 58 whose base 59 is secured to rubber pads 60 similar to the pads 16. These pads are secured by screws 61 and nuts 62 to the horizontal portions 63 of bracket arms 64 having flanged upper ends that are attached by screw bolts 65 to the pan 52. This pump 58 is preferably driven by a shaft 66 which has a spring and pin connection 67 to the lower end of the motor armature shaft 30.

Thus the motor 24 not only drives the fan 32, but also the pump 58 from the same armature shaft. By means of a short curved tube 67a the water of condensation is drawn from the pan 56 by the pump and discharged therefrom through a tube 68 that passes upwardly with the tubes 42 and 51 through the depending tube 9, ring 1 and ceiling 2 to a drain pipe (not shown).

In Figure 2 I have illustrated a wall bracket type of air conditioning fan. This type is in all respects similar to the fan which I have just described save that the tubular member 9 is attached at its upper end to the horizontal arm 69 of an ornamental wall bracket 70. The arm 69 is hollow to receive the refrigerant inlet tube 42, the gas outlet tube 51, and the condensation discharge tube 68. These tubes pass through the vertical portion of the bracket 70 and the wall 71 to which said bracket is secured by screws 72.

Mounted on the top portion of the outer end of the arm 69, directly above the air conditioning fan unit, is an indirect lighting lamp 73.

The wall bracket type of my air conditioning unit is so supported by the bracket that the conditioned air will be discharged laterally in all directions by the same.

In Figures 3 and 4 I have illustrated a pedestal

type of air conditioning unit. In these figures the pedestal comprises a column having a base 75 and a cap 76. The base, column and cap of the pedestal are hollow, and support an air conditioning fan unit of the general type disclosed in Figure 1.

Referring to Figure 4 for a detailed description of this fan unit, the numeral 77 designates a bottom water condensation pan that rests upon the top of the cap 76, which in turn surrounds and is supported by the upper end of the column 74.

Secured to the pedestal cap 76 by long screws 78 which pass downwardly through the pan 77 into the cap are the foot portions 79 of vertical 15 supporting members 80 which terminate at their upper ends in horizontal parts 81. Secured to the latter by studs 82 are vertical shafts 83 which, at their upper ends, support a plate 84 similar to the plate 17.

Secured to the plate 84 directly over the shafts 83, by long studs 85 which pass through them and the plate into the shafts 83, are rubber pads 86 similar to the pads 16. Attached to these pads are bracket arms 87 to the upper ends of 25 which a vertically disposed electric motor 88 is secured.

Surrounding this motor is a housing 89 having the shape illustrated in Figures 3 and 4. At its bottom edge the housing 89 is secured to foot 30 members 90 which are attached to the horizontal portions 91 of arms 92, by long studs 93. To the upper horizontal portions 94 of the arms 92 the housing 89 is attached by studs 95.

Secured to the plate 84 in two circumferential rows are rubber pads 96 similar to the pads 16. The horizontal portions 91 of the arms 92 are secured upon these two rows of pads by the studs 93. Attached to the bottom portions of these pads 96 by the same studs 93 are horizontal bars 40 97 to which U-rods 98, similar to the U-rods 35, are secured.

The U-rods 98 support an expansion coil 99 similar to the expansion coil 34. This expansion coil or evaporator 99 so supported by the U-rods 45 98, surrounds a centrifugal fan 100 of the multi-vane type similar to the fan 32. This fan 100 is mounted upon a hub 101 secured to the armature shaft 102 of the motor 88.

The fan 100 forces laterally between the coils of the evaporator 99, the air to be cooled by the latter and discharged laterally in all directions by the flat rings 103 similar to the rings 41 and mounted upon vertical studs 104. These studs depend in a circumferential series from the outer horizontal annular edge portion 105 of the plate 84. To the lower ends of the pins 104 the outer annular horizontal edge portion 106 of a condensation pan 107 is secured by nuts 108. This 60 pan, which is similar to the pan 52, has a central flanged neck portion 109 that surrounds the lower end of the fan 100.

Depending from the pan 107 around the upper ends of the vertical members 80, are studs 110 to 65 which the upper annular horizontal edge portion 111 of the pan 77 is secured by nuts 112.

Attached to the studs 110 are two flat rings 113 having downwardly inclined portions for deflecting the air that enters between them, downwardly and inwardly for entrance through the central open portions of said rings to the centrifugal fan 100, as indicated by the arrows in Figure 4.

For the purpose of removing the water of con- 75

densation which descends into the bottom pan 77 from the pan 107, I have provided a pump 114 similar to the pump 58. This pump is mounted upon a base plate 115 which is supported by rubber pads 78 that are secured to the foot portion 79 of the vertical members 80 by the screws 78. (See Figure 4.) The water of condensation from the pan 77 is drawn into the pump through a short curved tube 116, and discharged by said pump through a tube 117 that passes downwardly through the hollow pedestal to a drain not shown. The pump 114 is driven through a shaft 118 connected by a spring and pin connection 119 with the armature shaft 102 of the motor 88.

The liquid refrigerant is admitted through a tube 120 which passes from a compressor (not shown) through the hollow pedestal to a coil jacket or sleeve 121. This coil 121 surrounds the bracket arms 92 and is held against them by vertical retaining members 122 similar to the retaining members 44, and attached to said bracket arms by long studs 123. The lower end of the coiled liquid refrigerant inlet tube 120 communicates with an expansion valve 124, from whence the gaseous refrigerant flows through a tube 125 into the expansion coil 99 which surrounds the centrifugal fan 100, to cool the air set in lateral motion in all directions by the fan. Through a tube 126 connected with the outlet end of the expansion coil 99, the cooled gaseous refrigerant is discharged into a T-fitting 127 which communicates with the coil sleeve or jacket 121 that surrounds the inlet tube 120, to cool the warm liquid refrigerant that enters the latter.

The coil sleeve 121 terminates in a T-fitting 128 from which the gaseous refrigerant is returned to the compressor through a tube 129 which, with the liquid inlet tube 120 and condensation outlet tube 117, passes through the hollow pedestal to said compressor. (See Figures 3 and 4). Mounted on the top middle portion of the housing 89 is an indirect lighting lamp 130. (See Figure 3.)

In Figure 5 I have illustrated a ceiling type of fan unit that is constructed to receive air through the sides and top and discharge it laterally through the bottom. In this figure I have shown a ceiling-supported tubular member 131 to which bracket arms 132 similar to the bracket arms 13, are secured.

Vertical arms 133 terminating in the horizontal lower ends 134 are secured to the bracket arms 132. Rubber pads 135, similar to the pads 16, are secured to the ends 134 of the arms 133 to noiselessly support a plate 136 having a central opening 137.

Secured to rubber pads 138 fixed to the upper surface of the plate 136 around the opening 137, are bracket arms 139 which support a vertically disposed electric motor 140. Surrounding this motor 140 is a cylindrical housing 141 and a dome-shaped cover 142, the housing being mounted upon the horizontal portions 134 of the arms 133, while the cover depends from the tubular member 131.

Surrounding the arms 133 is a coiled sleeve 143 supported by retaining members 144 secured to said arms. Through this sleeve 143 there passes a tube 145 that conducts a liquid refrigerant downwardly through the tubular member 131 from a compressor not shown. Through an opening 146 in the top of the housing 141 air

enters the latter and passes downwardly in the direction of the arrows through the opening 137 in the plate 136 for circulation by a fan to be hereinafter described. (See Figure 5.)

At its lower end the liquid refrigerant inlet tube 145 communicates with an expansion valve 147 from whence the gaseous refrigerant flows through a tube 148 into an expansion coil 149 similar to the expansion coil 34 and similarly supported beneath the plate 136 by U-rods 150 connected to bars 151 secured to the pads 135. (See Figure 5.)

Depending from the outer, flat annular edge portion 152 of the plate 136, is a circumferential series of studs 153. Secured to these studs at suitable distances apart, are flat rings 154 between which air enters the unit for cooling by the refrigerant expansion coil 149 before being discharged by the fan soon to be described.

The moisture or water of condensation abstracted from the air by the expansion coil, drops upon a pan 155 which is secured to the lower ends of the studs 153 by nuts 156. This pan is formed at its middle portion with a wide opening 157 defined by an annular upturned flange 158. (See Figure 5.)

Mounted upon the bottom of the pan 155 around, and closely adjacent to, the flange 158, are rubber pads or feet 159 which support a base plate 160 having a downwardly projecting, internally threaded, hollow boss 161 through which the upper portion of a fan shaft 162 passes. This shaft is connected at its upper end by a coupling 163 to the armature shaft 164 of the motor 140.

Secured to the lower end of the armature shaft 164 is the rotor 165 of a rotary pump 166 mounted on the base plate 160, and which is in communication with the drip pan 155 through a tube 167 which enters the pan through a hole in its flange 158. The water of condensation drawn from this drip pan 155 by the pump 166 is forced by the latter into an outlet tube 167a which passes through the tubular member 131, adjacent the liquid refrigerant tube 145, to a drain, not shown.

The numeral 170 designates a multi-vane fan having a hub 171 attached to the lower end of the shaft 162. After passing the expansion coil 149, the air conditioned by the latter enters the fan 170 as indicated by the arrows in Figure 5, and by the fan is forced laterally in all directions through the openings defined by the flat rings 172 mounted on studs 173. These studs depend from the drip pan 155, and have secured to their lower ends, by nuts 174, a base pan 175 directly below the fan.

Through a tube 176 connected with the outlet end of the expansion coil 149, the cool gaseous refrigerant enters the tubular sleeve or jacket 143 to cool the warm liquid refrigerant which passes through the latter in the tube 145. The sleeve 143 terminates in a T-fitting 177 from which the gaseous refrigerant is returned to the compressor, not shown, through a tube 178 which passes through the tubular member 131 with the refrigerant inlet tube 145 and condensation discharge tube 167a. (See Figure 5.)

Having described my invention, I claim:

1. In a device of the type described, a support, a housing secured to said support, a centrifugal, multi-vane fan within said housing, a refrigerant-evaporator coil surrounding the fan within the housing, and spaced flat rings surrounding the evaporator coil, within the housing, to dif-

fuse the air conditioned by the coil laterally in all directions.

2. In a device of the type described, a support, a housing secured to said support, an electric motor within said housing, an armature shaft on said motor projecting axially of the housing, a centrifugal, multi-vane fan secured to said armature shaft within the housing, a refrigerant-evaporator coil surrounding the fan within the housing, and vertically spaced flat rings surrounding the evaporator coil, within the housing, to diffuse the air conditioned by the coil laterally in all directions.
3. In a device of the type described, a support, a housing secured to said support, an electric motor within said housing, an armature shaft on said motor, a fan secured to said armature shaft within the housing, a refrigerant-evaporator coil associated with said fan within the housing to condition the air forced past it by said fan, a pan in said housing to receive the water of condensation abstracted from the air by said refrigerant-evaporator coil, and a pump secured to said armature shaft for forcing the water of condensation from said pan.
4. In a device of the type described, a support, a housing secured to said support, an electric motor within said housing, an armature shaft on said motor projecting axially of the housing a fan secured to said armature shaft within the housing, a refrigerant-evaporator coil surrounding the fan within the housing, to condition the air forced past it by the fan, a drip pan at the bottom of said housing to receive the water of condensation abstracted from the air by said refrigerant-evaporator coil, and a pump attached to said armature shaft below the fan to force the water of condensation from said drip pan.
5. In a device of the type described, a support, a housing secured to said support, a vertically disposed electric motor within said housing, an armature shaft projecting downwardly from said motor, a centrifugal multivane fan mounted on said armature shaft within the housing, a refrigerant-evaporator coil surrounding said fan within the housing, and means for introducing air to said fan through the bottom and top of said housing, and means in the side of said housing adjacent the refrigerant-evaporator coil for discharging the air moved past said coil by the fan, laterally in all directions.
6. In a device of the type described, a hollow pedestal, a fan housing supported on said pedestal, a fan within said housing, a refrigerant-evaporator coil surrounding said fan within the housing to cool the air set in motion by the fan, vertically spaced members in said housing around the evaporator coil to diffuse the conditioned air laterally in all directions, a liquid refrigerant tube passing upwardly through said pedestal to the evaporator coil, and a gas discharge tube passing downwardly from said evaporator through said pedestal.
7. In a device of the type described, a hollow pedestal, a fan housing supported on said pedestal, a fan within said housing, a refrigerant-evaporator associated with said fan in said housing to cool the air set in motion by the fan, said housing formed with openings to discharge said air laterally in all directions, a pan below said evaporator to receive the water of condensation, a pump for drawing said condensation from the pan, a condensation discharge tube leading from said pump downwardly through said pedestal, a

tube for conducting liquid refrigerant to said evaporator and a tube for withdrawing gas from the latter, also in said pedestal.

8. In a device of the type described, a support, a housing secured to said support, a vertically disposed motor in said housing, an armature shaft projecting downwardly from said motor, a centrifugal, a multi-vane fan on said armature shaft, within the housing, a refrigerant-evaporator coil surrounding the fan within the housing, the bottom and top of said housing formed with openings to admit air to the fan, and spaced horizontal members defining openings in the side of said housing around the refrigerant-evaporator coil to diffuse outwardly in all directions the air forced past said coil by the fan.

9. The combination with a wall bracket having a hollow horizontal arm, a fan housing depending from the outer end of said arm, a fan in said housing, a refrigerant-evaporator surrounding the fan in said housing to cool the air set in motion by the fan, said housing having side openings for diffusing said air laterally in all directions, a liquid refrigerant tube passing through the hollow arm of said bracket to the evaporator, and a gas discharge tube connected to the latter and also passing through said hollow bracket arm.

10. In a device of the type described, a support, a housing secured to said support, a refrigerant-evaporator within said housing, means surrounding said evaporator to admit air laterally thereto, a fan in said housing below the evaporator, means for directing air cooled by the evaporator, to the fan, and means for diffusing laterally in all directions, the cool air set in motion by the fan.

11. In a device of the type described, a support, a housing secured to said support, an electric motor in said housing, an armature shaft projecting downwardly from said motor, a refrigerant-expansion coil surrounding said shaft within the housing, means surrounding the expansion coil to admit air laterally thereto, a fan operated by the armature shaft in said housing below the expansion coil, means for directing air cooled by the evaporator coil, to the fan, and means for diffusing laterally in all directions the cool air set in motion by the fan.

12. In a device of the type described, a support, a housing secured to said support, an electric motor in said housing, an armature shaft projecting downwardly from said motor, a refrigerant expansion coil surrounding said shaft within the housing, means surrounding the expansion coil to admit air laterally thereto, a fan operated by said armature shaft in said housing below the expansion coil, to set in motion and discharge the air cooled by said coil, a pan below the expansion coil to receive water of condensation from the latter, and a pump secured to said armature shaft between the motor and the expansion coil to remove the water of condensation from said pan.

13. In a device of the type described, a support, a housing secured to said support, a fan within said housing, a refrigerant-evaporator surrounding the fan within said housing, and diffusing means within the housing, surrounding the refrigerant-evaporator, to diffuse the air conditioned by the evaporator laterally in all directions.

14. In a device of the type described, a support, a housing secured to said support, a fan within said housing, a refrigerant-evaporator coil surrounding the fan within the housing, and spaced horizontal means defining openings in the housing around the refrigerant-evaporator coil, to diffuse

the air conditioned by said coil outwardly in all directions.

15. In a device of the type described, a support, a housing secured to said support, a fan within the housing, refrigerant-evaporator means associated with said fan within the housing to condition the air forced past it by said fan, a receptacle in the housing to receive the water of condensation abstracted from the air by said refrigerant-evaporator means, a pump for forcing the water of condensation from said pan, an electric motor within the housing, and means connected to the motor for operating both the fan and the pump.
- 15 16. In a device of the type described, a support, a housing secured to said support, a fan within the housing, a refrigerant-evaporator surround-

ing the fan within the housing, the bottom and top of said housing formed with openings to admit air to the fan, and spaced horizontal members defining openings in the side of said housing around the refrigerant-evaporator to diffuse outwardly in all directions the air forced past said coil by the fan.

17. In a cooling unit, the combination with a container having its opening directed upwardly, of a plurality of cooling coils supported within the container, a motor operated fan positioned within the coils and operating to draw air through the opening in the container, and louvers in the sides of the container for discharging the air and directing the same downwardly. 15

DON E. DASHER.
